Primary Examiner — Dominic Simone(74) Attorney, Agent, or Firm — McClure, Qualey & Rodack, LLP(57) CLAIM

The ornamental design of an athletic shoe with cleats, as shown and described.

DESCRIPTION

FIG. 1 is a left side elevational view of a sports shoe showing my new design;

FIG. 2 is a right side elevational view thereof;

FIG. 3 is a bottom plan view thereof;

FIG. 4 is a top plan view thereof;

FIG. 5 is a front elevational view thereof; and,

FIG. 6 is a rear elevational view thereof.

Broken lines throughout the figures show related environmental elements only and form no part of the claimed design.
